UNITED STATES PATENT OFFICE.

NELSON GOODYEAR, DECEASED, LATE OF NEW YORK, N. Y., BY KATHARINE F. GOODYEAR, ADMINISTRATRIX, OF NEW YORK, N. Y., ASSIGNOR, BY MESNE ASSIGNMENTS, TO THE PNEUMATIC ACETYLENE GENERATOR CORPORATION, A CORPORATION OF NEW YORK.

ACETYLENE-GENERATOR.

1,373,419.

Specification of Letters Patent.

Patented Apr. 5, 1921.

Application filed April 21, 1917. Serial No. 163,654.

To all whom it may concern:

Be it known that NELSON GOODYEAR, deceased, late a citizen of the United States, and formerly residing at #157 St. Nicholas 5 Ave., New York city, has invented certain new and useful Improvements in Acetylene-Generators, of which the following is a clear, full, and exact description.

The invention relates to valve controlling 10 means and more particularly to arrangements for controlling the feeding of carbide and the consequent generation of gas in acetylene generators. The invention is, however, capable of application to other 15 mechanism in which the parts are subjected to fluid pressure. The purpose of the invention is to produce a reliable pneumatic controlling device for gas generators or other apparatus to which its principles may 20 be applicable; to produce a complete, efficient and safe means of feeding or controlling the feed of gas generating materials, and to improve upon and lessen the cost of gas generators.

25 Heretofore it has been the practice in the class of generators best typified by acetylene generators, to cause or govern the feeding of the gas generating material by a movable controlling member, such for example 30 as a diaphragm or gasometer, acted upon by gravity or a spring in a direction tending to cause the generation of gas and acted upon by the pressure of the gas generated in a direction tending to arrest or stop the 35 generation of gas. This method permits dangerous leakage, a great waste of gas or possible explosion or bursting of the generator in case of the rupture or leakage of the movable controlling member. Flexible dia- 40 phragms provide a much simpler and less costly controlling means than gasometer or displacement holders, but the fear of their leakage has prevented their use except in very small apparatus.

45 With the object of overcoming these defects, in the invention herein disclosed and claimed the movable controlling member on one side is exposed to the pressure of a confined volume of gas or air from a pressure 50 chamber to move it in a direction tending to cause the generation of gas and expose the controlling member on the other side

to the pressure of the gas generated tending to move said member in a direction to stop the generation; said controlling member being at all times subjected to a constant force (such as gravity or a spring) 55 acting to move it in a direction to stop the generation of gas, so that when the pressures on opposite sides of the controlling member are balanced, as would occur through leakage or rupture of said controlling member, the generation will be arrested.

Another object of the invention is to provide simple means for safeguarding the 60 proper action of the generator, by utilizing the pressure of confined air or gas in a pressure chamber to act on the movable controlling member to cause the generation of gas and providing vents therefor coacting 65 with other parts of the generator to insure the escape of gas or air from the pressure chamber or to prevent the confinement of gas or air therein unless other conditions necessary to the safe and economical operation 70 of the apparatus obtain or are complied with.

Other specific objects of the invention are to provide a generator in which the gas feeding mechanism may be safely actuated by a diaphragm instead of by a gasometer 80 or displacement holder, in such a manner that the failure of the diaphragm through rupture or leakage will tend to prevent a further feeding of gas generating material, and with such a construction and disposition 85 of the parts that no escape of gas can occur outside of the apparatus in case of such failure of the diaphragm; to provide a gas generator adapted to work at any desired pressure without straining the actuating diaphragm; and to provide means for removing the force tending to cause the feeding of gas generating material in such a manner as to insure the safe operation of 90 the generator.

95 Further objects and advantages will appear from the following detailed description, taken in connection with the accompanying drawings, in which—

Figure 1 is a cross-sectional view through 100 the hopper and safety mechanism of a form of the invention adapted to general use;

Fig. 2 is an elevation of the charging lid for the hopper;

Fig. 3 is a cross-sectional view on line A—A of Fig. 1, looking down;

Fig. 4 is an elevation of the residuum discharge gate or flush-out mechanism;

5 Fig. 5 is a vertical cross-section of another embodiment of the invention more specifically adapted to relatively small or portable apparatus;

10 Fig. 6 is a detailed enlarged section of parts 16, 17, 18 and 20 of Fig. 5;

Fig. 7 is a top view of lever 31 shown in Fig. 5; and

15 Fig. 8 is a sectional view of an air pump adapted for use with the generators as explained in the following specification.

In Fig. 1, 1 is a hopper adapted to contain calcium carbid or other suitable generating material in granular form. 2 is a generator tank on which the hopper 1 is supported by 20 the neck casting 26 and the hopper casting 23, provided with the gasket 24. The lower part of the hopper 1 has a downwardly converging conical bottom 5, which is fastened to the hopper casting 23. The hopper casting 23 supports on its underside a valve seat 41 both conforming to the lines of the conical bottom 5 of the hopper. The valve seat 41 is provided with a feed orifice 6 adapted to be closed by the valve 7 guided at its upper end on the rod 8. The hopper casting 23 is provided with three arms 9 extending inwardly and upwardly and supporting the diaphragm seat 10. One of these arms 9 has a duct 11 running through it. The arms 35 9 carry a housing or shield 12 adapted to keep the weight of the gas generating material from interfering with the movement of the valve 7 or its attached parts. An annular diaphragm 13 is clamped at its inner 40 edge to the seat 10 by means of the flanged spider 14 and rod 8, which is threaded at its upper end for the purpose. At its outer edge the diaphragm 13 is clamped between the two flanges 15 and 16, which in turn 45 carry a diaphragm casing or pressure chamber 17 which is so fastened to the flange 15, as by soldering or other means, to make a gas-tight joint. The pressure chamber 17 may be provided at its upper end with a 50 guide rod 18 adapted to slide in a guide 19 fastened to the housing 12. The flange 16 is provided with three downwardly extending rods or bolts 20, fitted to slide freely through holes in the upper expanded portion 55 21 of the valve 7 and serve to lift the valve whenever the pressure chamber 17 is forced upward beyond a certain point. A certain amount of space for lost motion is allowed, by a proper provision in the lengths 60 of the rods 20, between the top of the valve casting 21 and the bottom of the flange 16, so that the pressure chamber 17 may have some play downwardly in case the valve 7 is seated on the valve seat 41. The valve 7 65 with its expanded portion 21 is of consider-

able weight so that the tendency of the valve is to close securely by gravity against any passage of gas generating material, though it is not necessary that the valve 7 seat in a gas-tight manner against the extension 41. 70

Means are provided for lifting the valve manually by means of the lever 22, dog 24 and rock shaft 25, which extends through a stuffing box 26, as shown in Fig. 3. The outer end of the rock shaft 25 may be provided with a handle or lever 27, having a weighted end 28 for the purpose of rotating the rock shaft 25 in a direction tending to permit the valve to close. 75

A charging lid 29 provided for the hopper 80 has a gasket 30 adapted to make a pneumatic seal when pressed against the rim 31 of the cover plate 32, which latter is secured to the top of the hopper 1 by the bolts 33 and flange 34. The cover plate 32 is provided to give 85 ready access to the mechanism within the hopper, excepting the valve 7, lever 22 and dog 24 which may be removed or inserted by taking off the valve seat 41. The charging lid 29 is held to its seat by a strong spring 35, which is compressed by the clamping lever 36 which is pivoted at 70. The charging lid 29 is connected to the clamping lever 36 by the bolt 37, which is slidable at its upper end through said lever. A swinging yoke 38 loosely pivoted to the cover plate 32 and provided with a clamping screw 39 is adapted to hold the clamping lever down. On the lid 32 is mounted a valve casing 40 carrying a valve 43 having an upwardly extending valve stem 72 which causes the valve 43 to close tightly against the seat 71 when the lever 36 is forced down. The seat 71 surrounds the end of the tube 44, which extends downwardly and communicates with the pressure chamber 17 by way of the duct 11. The clamping screw 39 is not long enough to reach the valve stem 72 when the clamping lever is swung to open the charging lid. A spring 45 is provided to open 100 the valve 43 whenever the pressure on it is removed by turning the clamping screw 39 upward. The spring 35 keeps the charging lid 29 tightly against its seat unless the clamping screw 39 is screwed up so far that the clamping lever 36 engages with the head of the bolt 37, which prevents any further distension of the spring 35. The length of the bolt 37 is such that a certain amount of play is provided between the clamping lever 36 110 and the head of the bolt in order to permit the clamping lever 36 to be raised sufficiently to permit the valve 43 to open, without taking the pressure off the charging lid 29. Any escape of gas from the valve casing 40 115 is prevented by the small flexible diaphragm 42. A suitable check valve 47, shown in detail in Fig. 6, is provided in communication with the duct 11. This check valve has a seat 21' adapted to engage the nozzle 22' 120

125

130

of an air pump of the type shown in Fig. 8. Mounted on the top of the generator tank 2 is a safety valve housing 48, which is in communication with the inside with the generator tank. The housing 48 has an inward extension 49 adapted to carry a valve seat 50. Coacting with the valve seat 50 is a valve 53 having a disk of rubber 51 or other suitable material which may be made integral with the flexible portion of the diaphragm 52. The flexible diaphragm 52 is attached to the outer rim of the valve 53 by the collar 111 and both permits of and causes the movement of valve 53 when acted upon by gas pressure. Above the diaphragm 52 is a smaller flexible diaphragm 54 connected to the upper part of the valve 53 and with the cover plate 55 of the safety valve housing 48. The space 73 between the diaphragms 52 and 54 is connected by the duct 56, tube 57 and duct 11 with the interior of the pressure chamber 17. The lower part of the duct 56 has an extension 58 provided with a valve seat 59 and valve 60, which is connected by the divided link 61 with the weighted lever 74 which normally keeps said valve closed. The valve 53 is provided with a slotted stem 62 slidably supported in the guide 63 carried on the cover plate 55. Through the slot 69 in the stem 62 passes a locking bar 64, which is provided with a sloping or wedge-shaped surface 65 which serves to force the valve extension 62 upwardly when the locking bar 64 is slid farther into the slot. The locking bar 64 is cut away at 66 to permit the firm seating of the valve 53 and to form a shoulder 67 so as to prevent the locking bar 64 from being slid farther into the slot when the valve 53 is on its seat.

Provision is made for filling the generator tank 2 with water by means of the funnel 80, pipes 77 and 79. The pipe 77 is provided with a flat head cock 78, having a handle 119. The locking bar 64 is provided with a keyhole shaped opening 83, the slotted portion of which 81 is adapted to slide over the flat head 82 of the cock 78 in such a manner that the cock is locked in closed position when the locking bar 64 is slid to the left or in a direction to permit the stem 62 to descend and the valve 53 to close, but when the locking bar is slid to the right in a position to force the stem 62 upward, raising the valve 53 from its seat 50, the circular portion 83 of the keyhole shaped opening is slid over the head 82 of the cock 78 so as to permit the cock to be opened or closed at will, but when the cock 78 is in the open position, the locking bar 64 is held by the head 82 in a position to lock the valve 53 open.

The generator tank is provided with a residuum discharge gate 92, shown in Figs. 3 and 4, provided with the yoke 93 which

carries a spring 120 adapted to press on a closure or valve 121 which rotates on the cylindrical surface 122. To open the residuum gate 92 the yoke must be moved upward by the handle 94. Pivotally mounted over the center of the residuum gate 92 is a hollow shaft 86 which extends upwardly through a bracket 89 shown in Fig. 1, and terminates in a head casting 85, which is provided with a flattened portion 84, which passes through another keyhole shaped opening in the other end 87 of the locking bar 64, exactly similar to that described for cock 78. The lower end of the shaft 86 is provided with an arm 91, having an extension 90 adapted to prevent the opening of the residuum gate 92 when in the position shown in the drawings. In order to open the residuum gate 92 or the cock 78, it is necessary to first raise the extension 62 of the valve 53 slightly and then push the locking bar to the right as far as possible into the slot 69, which brings the circular portions of the keyhole shaped openings in the locking bar 64 into a position to permit the turning of the handle 119 to open the cock 78 or the turning of the handle 88, head piece 85, shaft 86, arm 91 and extension 90 into a position to permit the opening of the residuum gate 92. Handle 88 is provided to facilitate the rotation of the shaft 86 and attached parts, and coacts with the side of the generator tank 2 to prevent said shaft and parts from being turned in the wrong direction. It will be seen that when the extension 62 of the arm 91 is swung around to permit the opening of the residuum gate 92 and the gate is opened, the arms of the yoke 93 will prevent the rotation of the shaft 86 and its attached parts into the position shown in the drawings, and when the shaft 86 is turned into the position permitting the opening of the residuum gate 92, the flat portion 84 of the head 85 holds the locking bar in a position to maintain the valve 53 in an open position. Similarly, when the cock 78 is in the open position, the flat portion of its head 82 prevents the locking bar from being slid into a position to permit the closing of valve 53. Attached to the collar 111 of the valve 53 is a divided link 99 fastened to a lever 100, which is pivoted on the lugs 101. The outer end 123 of the lever 100 is fashioned so that it will strike the stop 102 on the divided link 61 so as to open the valve 60 whenever the extension 62 is raised and the valve 53 is open. It will thus be seen that whenever the water charging cock 78 or the residuum gate 92 can be opened, the valves 53 and 60 are locked open and that the valves 53 and 60 cannot be closed unless the water charging cock 78 and discharge gate 92 are locked shut.

To prevent overfilling of the generator tank 2 with water, a float 107 is provided

which telescopes over the lower end of the pipe 79, on which are formed guiding and spacing lugs 109. The float 107 is annular in form having a tubular center 108, which with the pipe 79 is adapted to form a gas seal when the tubular center 108 is filled with water. The lower end of the tubular center 108 is provided with a pad of rubber or other suitable material 124, which is 10 adapted to form a practically tight closure for the pipe 79 when the float 107 is in its upward position as shown in the drawings. When there is no water in the generator tank 2, the float will descend so as to give a 15 full opening at the bottom of the pipe 97 into the tubular center 108 of the float 107, and when water enters through these parts from the funnel 80 it overflows at the top of the tubular center 108 and tends to keep 20 the top of the float clean.

The float 107 is connected by links 105 with the split end of lever 103, which is pivoted at 104 on the brackets 112, which are attached to or are integral with the housing 48. The lever 103 is provided with an arm carrying a lug 106 adapted to engage the underside of the lever 74 so as to raise it, the divided link 61, and the valve 60, whenever the float 107 falls. The weight of the 25 float 107 is sufficiently in excess of the weight 125 on the lever 74 to insure the opening of the valve 60, but the buoyancy of the float is sufficient to raise it so that the pad 124 exerts considerable pressure on the bottom 30 of the pipe 79 when the generator tank 2 is filled to the intended working level of the water in said tank, which is about as shown 35 in the drawing of Fig. 1.

On filling the generator tank 2, the float 40 will rise and prevent any further introduction of water as soon as the proper level is reached, which will be indicated by the filling up of the pipes 79 and 77, until it can be seen to stand in the bottom of the funnel 45 80, which is an indication that the generator has been filled to the proper level.

The valve 53 serves to vent the generator to the outer air through the extension 49 whenever the generator is being filled with 50 water or whenever water or residuum is withdrawn from the generator through the residuum gate 92, and this venting is positively insured through the interlocking mechanism previously described. The hydraulic seal formed by the water in the 55 tubular center 108 prevents any gaseous mixtures escaping through the funnel 80 and connecting pipes.

The operation of the generator is as follows. After the generator tank 2 and the 60 hopper 1 have been filled respectively with water and calcium carbide in granular form, the cock 78 and the charging lid 29 are closed and the locking bar 64 is slid so as 65 to lock the residuum gate and cock 78 shut.

Then the clamping screw 39 is screwed down, tightly closing the valve 43. In order to start the generator, the nozzle 22' of an air pump similar to that shown in Fig. 8, is inserted in the seat 21' of the check valve 70 47, and air is pumped through the duct 11 into the pressure chamber 17 which is expandable by reason of its lower portion being formed by the flexible diaphragm 13. As the pressure chamber expands, the upper portion rises and carries the flange 16 and bolts 20 upward until the heads of the bolts 20 engage the expanded portion 21 of the valve 7, which raises said valve permitting the carbide to flow through the orifice 6 into the water in the generator tank. When sufficient carbide has been fed into the water, enough gas will be formed to raise the pressure in the generator and hopper so as together with the weight of the chamber 17 and attached parts, to overbalance the pressure within the pressure chamber 17 which will then move downwardly, permitting the valve 7 to return to its seat and prevent any further flow of carbide to the water. 80 The pressure at which the generator produces gas is therefore governed by the pressure in the pressure chamber 17, which latter may be controlled at will by means of the pump. The pressure chamber 17 is 85 made of considerable weight of wall so as to guard against its being crushed in or distorted by gas pressure in the hopper external to it, and also for the purpose of causing it to descend by gravity, which latter action is also aided by making the flange 16 as heavy as possible compatible with the space available. On account of the weight 90 of the chamber 17 and flange 16, the air within the chamber 17 is subjected to a considerably greater pressure than the gas outside of the chamber 17 within the hopper 1. It is this excess of air pressure within the pressure chamber which causes it to rise 95 carrying the heavy valve 7 upward when the pressure in the generator and hopper 100 are reduced by gas being drawn off.

If at any time the diaphragm 13 should become ruptured or leak, the pressure within the chamber 17 will diminish to that 115 within the hopper outside of the chamber 17, and the chamber and attached parts will fall closing the valve 7. In this manner the danger caused by the possibility of rupture of the diaphragm is avoided. In all the 120 older types of acetylene generators actuated by diaphragms, a leakage of the diaphragm would cause a continual feeding of carbide with one of two results; either the gas generated would escape into the building in 125 which the generator is housed, which would cause danger of explosion from the possibility of ignition of the escaping gas, or, in generators having the diaphragm entirely incased, the pressure within the generator 130

would rise to the bursting point of the apparatus.

When pressure is applied to the inside of the pressure chamber 17, the same pressure is communicated to the space 73 between the diaphragms 52 and 54, through the tube 57 and the duct 56. In the construction of this type of apparatus the diaphragm 54 should be larger than the area of the valve seat 50, 10 and the diaphragm 52 should be considerably greater in area than the diaphragm 54. The reason for this will be apparent from the following. Besides acting as a vent, the valve 53 forms a relief valve or safety 15 valve, and so long as the pressure within the pressure chamber 17 and the space 73 above the diaphragm 52 is greater than that within the generator tank 2, the valve 53 is held tightly against its seat 50 by the pressure of 20 the gas or air upon the top of the diaphragm 52. When, however, the generator is in operation so that the pressure within it becomes substantially greater than that of the outside atmosphere, the valve 53 will open 25 by reason of the pressure against the diaphragm 54 whenever the gas pressures in the generator tank 2 and space 73 are balanced. A balancing of this pressure will occur if either valve 43 or valve 60 is opened, or if 30 either diaphragm 52 or diaphragm 13 is ruptured or became leaky. If diaphragm 54 should leak, the pressure in the pressure chamber 17 could not be maintained and the generator could not be started. If, for 35 any reason, the valve 7 is prevented from entirely stopping the flow of carbid through the opening 6, as might occur if it were held up by some foreign body being stuck between the valve and its seat, the pressure 40 will rise within the generator, forcing down or collapsing the pressure chamber 17 until the latter has reached the lower limit of its travel, during which time the gas or air within the pressure chamber 17 will continu- 45 ally rise also, still being greater in amount than the pressure outside of the chamber 17 in the hopper 1 by reason of the weight of the chamber and flange 16 as previously explained. But when the pressure chamber 50 17 has reached the lower limit of its travel and the diaphragm 13 is pressed upward by external pressure against the flange 15, no further compression of the air within the chamber 17 can occur, and as soon as the ex- 55 ternal pressure within the hopper and generator tank equals that within the pressure chamber 17 and space 73, the diaphragm 52 will be balanced as regards pressure and diaphragm 54 would open the relief valve 60 53. The valve 53 will remain open until the pressure within the generator has fallen to a point below that in the pressure chamber 17. If ever the generator tank 2 or residuum gate 92 becomes leaky, or if the 65 generator tank is not filled to the proper

level, or if the float 107 should leak, the float will fall, the lever 103 acting to open the valve 60 as previously described. This insures the restoration of equal pressures both inside and out of the pressure chamber 17 and the space 73, the closure of the valve 7 and the opening of the vent valve 53. As will be seen, this construction also prevents the starting of the generator if any of the last mentioned abnormal conditions 75 occur.

To guard against the charging lid 29 being opened when the generator is in operation, sufficient play is provided between the lever 36 and the yoke 38 to permit the valve 80 43 to be opened before the tension is taken off of the spring 35 by the screw 37. This insures the venting of the pressure chamber 17 which allows the valve 7 to fall preventing any further flow of carbid through the 85 orifice 6. This mechanism also provides for the venting of the pressure chamber 17 at all times when the lever 36 and charging lid 29 are thrown back to permit a filling of the 90 hopper, so that it is impossible by means of the pump (Fig. 8) or otherwise, to create a pressure in said chamber to cause the automatic operation of the generator.

The handle 27, rock shaft 25, dog 24 and the lever 22 are provided to manually raise 95 the valve 7 as an alternate method of charging the pressure chamber 17, in which case the pump may be dispensed with. In using this method the generator is charged with carbid and water as previously described, all 100 openings are closed, but the clamping screw 39 is not screwed down tight so as to close valve 43. Then the valve 7 is raised manually by means of the lever 27 and connecting parts and pressure is allowed to accumulate 105 to any desired amount in the generator, and pressure chamber 17, gas having access to the latter by way of valve 43, pipe 44 and duct 11. When the pressure gage 118 indicates that the desired pressure is reached, 110 the clamping screw 39 is screwed down closing the valve 43 which confines the pressure within chamber 17. The apparatus is now ready for automatic action when gas is withdrawn. Gas is withdrawn from the generator 115 to the service pipes through the opening 115 which may be provided with a pressure reducing valve 116 to which the service pipes are connected at 117.

A pressure gage may be dispensed with in 120 generators of this type, provided they are adapted to be started by means of a hand operated pump only. In this case the piston of the pump is made sufficiently large in area to prevent the possibility of attaining 125 a dangerous pressure by manual operation. It should, however, be understood that the limit of pressure in apparatus of this kind is governed solely by the strength of the walls of the apparatus as the method of con- 130

trol is such that there is no danger of straining the actuating diaphragm on both sides of which the pressure is substantially balanced.

5 It will be understood that, broadly speaking, the method of control for gas generators or other apparatus heretofore described, may be considerably modified without departing from the spirit of the invention, and 10 to illustrate this fact I have shown another embodiment of the invention in Figs. 5, 6 and 7.

In the type of generator shown in Fig. 1, the carbid feeding valve opens upwardly 15 and the pressure chamber 17 is also adapted to move, whereas in the embodiment of the invention shown in Fig. 5, the carbid feeding valve 7' opens downwardly and the pressure chamber 13' is stationary.

20 In this alternate form 2' is the generator tank to which the carbid hopper 1' is hinged at 25' so that the hopper may be swung over in order to give access to the generator which is filled with water through the opening in the neck casting 26'. When the hopper is swung over to give access to the tank 2', the hopper charging lid 41' will be at the upper portion of the hopper. The valve 7' is actuated by the diaphragm 9' which is 25 normally pulled upward by the spring 12' closing the valve 7'. As in the previously described apparatus, the opening of the valve is accomplished by means of confined pneumatic pressure within the pressure chamber 30 13' and in this form the pressure is produced by means of an air pump of which the nozzle 22' engages the seat 21' of the check valve 20', passes through the cock 18' and enters the pressure chamber by way 35 of the pipe 17' and 14'. At the bottom of the pipe 14' is a chamber 15' provided with a valve 16' adapted to be held tightly 40 against the bottom of the chamber 15' by the lever 31' which is pivoted at 32' and provided with a ball float 35' attached to its outer end at 38' by the rod 34'. The strength of 45 the spring 12' is far greater than that necessary to overcome the weight of the diaphragm 9', rod 8', valve 7', so that it will be understood that the pressure within the 50 chamber 13' must be considerably greater than that within the generator tank and hopper 1, in order to move the valve 7' downwardly to cause the feeding of carbid. 55 Therefore, any reduction of pressure within the chamber 13' down to or below that within the hopper 1, will permit the spring 12' to hold the valve 7' tightly against the seat and the valve 16' coacting with the float 60 35' is provided to accomplish this venting of the pressure chamber 13' in case the generator tank 2' is not charged with water to the proper level, or in case at any time 65 the generator tank should become leaky.

65 To guard against the generator being

opened when the feed valve is in operative position, the following means are provided:

The hopper is clamped to the generator tank by means of the hinge 25' and swing bolt 27' which is pivoted at 28' and engages 70 lugs 30' on a hopper casting 23', by means of the nut 29'. A cock 18' is mounted immediately over the lugs 30' and provided with a handle 19' adapted to interfere with the handles of the nut 29' unless the handle 75 19' of the cock is swung in the direction indicated by the arrow 42', Fig. 6. The cock 18' is provided with side outlet 39' and when the handle 19' is swung out of the way of the handles of the nut 29', the port 38' opens 80 into the pipe 17' connecting with the pressure chamber 13' by way of the pipe 14', and the port 37' of the cock 18' is brought opposite the side outlet 39', which action relieves the pressure from the pressure chamber 13' 85 causing the closing of the valve 7'. It will, therefore, be understood that the swing bolt 27' cannot be loosened without putting the generator out of automatic action. It will also be understood that the pressure chamber 90 13' cannot be charged with air when the hopper is swung over to be charged with carbid or for the purpose of introducing water into the tank 2', because in such event the valve 16' which slides loosely in chamber 95 15' would be out of contact with the lever 31' so that no pressure could be created or maintained in the pressure chamber. The plug of the cock 18' is made blind opposite the port 38' so that when the cock is turned 100 100 to permit the manipulation of the nut 29' of the swing bolt 27', entrance to the pressure chamber from the check valve 20' will be shut off. This necessitates the handle of the cock being turned into the position 105 shown in the drawing before the generator can be started.

The type of generator shown in Fig. 5 is more specially adapted to portable or outdoor use and it is not, therefore, necessary 110 to provide it with venting means for the generator tank 2', other than that provided in the opening in the neck casting 26'. Interlocking mechanism for the flush-out gate 4' is unnecessary because proper venting to 115 permit the residuum to be flushed out as provided by the unjoining of the hopper and safety against the continuation of generation in case the gate 4' were left open is provided by the provision of the valve 16' 120 coacting with the float 35' as previously explained.

Since the valve 7' cannot be opened except by an excess of pressure in the pressure chamber 13' over that in the hopper 1, it is 125 obvious that a rupture or leakage in the diaphragm 9' would cause the pressures on the two sides thereof to be equalized, which would permit the spring 12' to act to close the valve 7' tightly. The joint between the 130

hopper casting 23' and neck casting 26' is made tight by means of a gasket 24' of rubber or other suitable material. Provision for carrying off the gas to the point of use 5 is made as shown at 3'.

While I have shown and described certain specific forms and details of my invention, it is to be understood that the principle thereof is capable of embodiment in a wide 10 range of equivalents, and that though the invention has been explained in connection with its application to acetylene generators, it may be applied to a variety of devices in which it is desirable to control fluid pressure 15 in the manner herein indicated.

What I claim as new is:

1. In combination, a receptacle having an opening for connection to a source of gas supply under pressure, a valve for said opening, pneumatic means having no communication 20 with said aforementioned opening at any time for opening said valve and non-pneumatic means for closing said valve when said pneumatic means ceases to be 25 effective.

2. In combination, a receptacle having an opening for connection to a source of gas supply under pressure, a valve for said opening, automatic non-pneumatic means for 30 holding said valve closed, and pneumatically operated means having no communication with said aforementioned opening at any time for opening said valve in opposition to said automatic non-pneumatic means.

3. In combination, a container having an opening communicating with a source of gas supply under pressure, a valve for said opening, a movable member having one side exposed to the pressure of the gas in said container, said valve being connected to said member and movable therewith, means having no communication with said opening at any time for producing pneumatic pressure 40 on the other side of said movable member in excess of the pressure in said container to cause said member to move in a direction to open said valve, and means acting in opposition to such movement of the member and operating to close the valve when the difference 45 in pressure on opposite sides of the member is reduced.

4. In combination, a container having an opening communicating with a source of gas supply under pressure, a valve for said opening, means connected to said valve tending 55 to hold it closed, a pressure chamber associated with said container, a flexible diaphragm separating the interiors of said pressure chamber and said container and connected to said valve, means for maintaining different relative pneumatic pressures in said receptacle and pressure chamber to cause said diaphragm to coöperate with or oppose said first named means thereby to 60 close or open said valve.

5. In an acetylene generator, a generator tank, a carbide receptacle having a feed orifice in its bottom, a feed valve for said orifice, a flexible diaphragm to which said valve is connected, said diaphragm having 70 one side exposed to the pressure of the gas in said carbide receptacle, and means for maintaining different pneumatic pressure on the other side of said diaphragm to regulate the position of said valve, and means 75 for causing said valve to close in the event of rupture of said pneumatic means.

6. In combination, a receptacle having an opening for connection to a source of a gas supply under pressure, a valve for said opening, and pneumatic means for opening said valve comprising means for maintaining the valve-opening pneumatic pressure in said means, said pneumatic means having no communication with said opening, and 80 means for causing said valve to close in the event of rupture of said pneumatic means.

7. In combination, a receptacle having an opening for connection to a source of a gas supply under pressure, a valve for said opening, pneumatic means for opening said valve comprising means for maintaining the valve-opening pneumatic pressure in said means, and means comprising a flexible diaphragm 90 for separating the pneumatic pressure of 95 said means from that of said gas supply, and means for causing said valve to close in the event of rupture of said pneumatic means.

8. In combination, a receptacle having an 100 opening for connection to a source of gas supply under pressure, a valve for said opening, pneumatic means having no communication with said source of gas supply for effecting the opening of said valve and 105 for maintaining a predetermined opening pressure thereon, and means through which the valve-opening pressure may be neutralized through the increase in the pressure of the gas supply, and means for causing said 110 valve to close in the event of rupture of said pneumatic means.

9. In combination, a receptacle having an opening for connection to a source of gas supply under pressure, a valve for said opening, pneumatic means having no communication with said source of gas supply for effecting the opening of said valve and for maintaining a predetermined opening pressure thereon, means through which the valve 115 opening pressure may be neutralized through the increase in the pressure of the gas supply, and non-pneumatic means for automatically closing said valve when said pneumatic means ceases to be effective.

10. In an acetylene generator, a generator tank, a carbide receptacle having a feed orifice in its bottom, a feed valve for said orifice, a flexible diaphragm to which said valve is connected, said diaphragm having one side 130

exposed to the pressure of the gas in said carbid receptacle, means for closing said valve when the pneumatic pressures on opposite sides of said diaphragm are approximately equal, and means for causing a difference in pressure on the sides of said diaphragm in opposition to said means sufficient to open said valve.

11. In an acetylene generator, a generator tank, a carbid receptacle surmounting said tank and having a feed orifice opening thereto, a valve for said orifice, means tending to close said valve, a cup-shaped pressure chamber associated with said carbid receptacle, a diaphragm between the open end of said pressure chamber and said carbid receptacle, and flexibly connecting the same to permit movement of the pressure chamber, means connecting said valve to said pressure chamber and diaphragm, and means for creating a pressure in said pressure chamber sufficiently in excess of the pressure in said carbid receptacle to cause said pressure chamber to move in a direction to open said valve.

12. In an acetylene generator, a generator tank, a carbid receptacle surmounting said tank and having a feed orifice opening thereto, an upwardly opening valve for said orifice, means tending to close said valve, an inverted cup-shaped pressure chamber associated with said carbid receptacle, a diaphragm between the lower end of said pressure chamber and said carbid receptacle and flexibly connecting the same to permit a vertical movement of the pressure chamber, means connecting said valve to said pressure chamber and diaphragm, means for creating a pneumatic pressure in said pressure chamber sufficiently in excess of the pressure in said carbid receptacle to cause said pressure chamber to move upwardly to open the valve.

13. In an acetylene generator, a generator tank, a carbid receptacle surmounting said tank and having a feed orifice opening thereto, an upwardly opening valve for said orifice, means tending to close said valve, an inverted cup-shaped pressure chamber associated with said carbid receptacle, a diaphragm between the lower end of said pressure chamber and said carbid receptacle and flexibly connecting the same to permit a vertical movement of the pressure chamber, means connecting said valve to said pressure chamber and diaphragm, means for creating a pneumatic pressure in said pressure chamber sufficiently in excess of the pressure in said carbid receptacle to cause said pressure chamber to move upwardly to open the valve, and manually operated means to open said valve.

14. In an acetylene generator, a generator tank, a carbid receptacle surmounting said tank and having a feed orifice opening thereto, an upwardly opening valve for said orifice, means tending to close said valve, an

inverted cup-shaped pressure chamber associated with said carbid receptacle, a diaphragm between the lower end of said pressure chamber and said carbid receptacle and flexibly connecting the same to permit a vertical movement of the pressure chamber, means connecting said valve to said pressure chamber and diaphragm, means for creating a pneumatic pressure in said pressure chamber sufficiently in excess of the pressure in said carbid receptacle to cause said pressure chamber to move upwardly to open the valve, and automatic means for reducing the difference between the pressures in said carbid receptacle and said pressure chamber to permit said valve to drop to closed position.

15. In an acetylene generator, a generator tank, a carbid receptacle on said tank and having a feed orifice opening thereto, a feed valve for said orifice, means normally holding said valve closed, pneumatic means for holding said feed valve open against the force of said first named means, and means for rendering said pneumatic means inoperative, said last named means being responsive to an abnormal condition in the generator tank.

16. In an acetylene generator, a generator tank, a carbid receptacle having a feed orifice opening into said generator tank, a feed valve for said orifice, means normally holding said feed valve closed, pneumatic means for opening said feed valve against the force of said first named means, a water inlet pipe for said generator tank, a valve in said pipe, means for locking said valve in closed position, and means operable by the releasing movement of said locking means to render said pneumatic means inoperative, thereby permitting said feed valve to close.

17. In an acetylene generator, a generator tank, a carbid receptacle having a feed orifice opening into said generator tank, a feed valve for said orifice, means normally holding said feed valve closed, pneumatic means for opening said feed valve against the force of said first named means, a water inlet pipe for said generator tank, a valve in said pipe, means for locking said valve in closed position, and means operable by the releasing movement of said locking means to render said pneumatic means inoperative, thereby permitting said feed valve to close, the opening of said valve in the inlet pipe operating to lock said mechanism in position to maintain said pneumatic means inoperative.

18. In an acetylene generator, a generator tank, a carbid receptacle surmounting said tank and having a feed orifice opening thereto, an upwardly opening carbid feed valve for said orifice, means tending to close said feed valve, a pressure chamber associated with said carbid receptacle, a diaphragm between the lower end of said pressure chamber and said carbid receptacle and flexibly

- connecting the same to permit a vertical movement of the pressure chamber, means connecting said feed valve to said pressure chamber and diaphragm, means for creating a pneumatic pressure in said pressure chamber sufficiently in excess of the pressure in said carbid receptacle to cause said pressure chamber to move upwardly to open the valve, a water inlet pipe for said generator tank, a valve in said water inlet pipe, releasable means for locking the valve in the water inlet pipe in closed position, and means operable by the releasing movement of said locking means to reduce the pressure in said pressure chamber to cause the closing of said carbid feed valve.
19. In an acetylene generator, a generator tank, a carbid receptacle on said tank and having a feed orifice opening thereinto, a carbid feed valve for said orifice, means normally holding said feed valve closed, pneumatic means for holding said feed valve open against the force of said first named means, a residuum discharge gate for said generator tank, a movable stop adapted to be moved into position to prevent the opening of the residuum discharge gate, means for locking said stop in such position, and means operable by the releasing movement of said locking means to render said pneumatic means inoperative.
20. In an acetylene generator, a generator tank, a carbid receptacle on said tank and having a feed orifice opening thereinto, a carbid feed valve for said orifice, means normally holding said feed valve closed, pneumatic means for holding said feed valve open against the force of said first named means, said carbid receptacle having a charging opening provided with a cover, means for locking the cover in closed position, and means operable by the initial unlocking movement of said locking means to render said pneumatic means inoperative.
21. In an acetylene generator, a generator tank, a carbid receptacle on said tank and having a feed orifice opening thereinto, an upwardly opening valve for said orifice, means tending to close said valve, said carbid receptacle having a charging opening provided with a cover, means for locking said cover in closed position, an inverted cup-shaped pressure chamber associated with said carbid receptacle, a diaphragm between the lower end of said pressure chamber and said carbid receptacle and flexibly connecting the same to permit a vertical movement of the pressure chamber, means connecting said valve to said pressure chamber and diaphragm, means for creating pneumatic pressure in said pressure chamber sufficiently in excess of the pressure in said carbid receptacle to cause said pressure chamber to move upwardly to open the valve, means for reducing the difference between the pressures in
- in said carbid receptacle and in said pressure chamber to permit said valve to close, said last named means operable by the initial movement of the locking means for the cover of the carbid receptacle to release the same.
22. In an acetylene generator, a generator tank, a carbid receptacle surmounting said tank and having a feed orifice opening thereinto, an upwardly opening valve for said orifice, means tending to close said valve, an inverted cup-shaped pressure chamber associated with said carbid receptacle, a diaphragm between the lower end of said pressure chamber and said carbid receptacle and flexibly connecting the same to permit a vertical movement of the pressure chamber, means connecting said valve to said pressure chamber and diaphragm, means for creating a pneumatic pressure in said pressure chamber sufficiently in excess of the pressure in said carbid receptacle to cause said pressure chamber to move upwardly to open the valve, and automatic means for reducing the difference between the pressures in said carbid receptacle and pressure chamber to permit said valve to close under the action of said first-named means.
23. In an acetylene generator, a generator tank, a carbid receptacle surmounting said tank and having a feed orifice opening thereinto, an upwardly opening valve for said orifice, means tending to close said valve, an inverted cup-shaped pressure chamber associated with said carbid receptacle, a diaphragm between the lower end of said pressure chamber and said carbid receptacle and flexibly connecting the same to permit a vertical movement of the pressure chamber, means connecting said valve to said pressure chamber and diaphragm, means for creating a pneumatic pressure in said pressure chamber sufficiently in excess of the pressure in said carbid receptacle to cause said pressure chamber to move upwardly to open the valve, and means for reducing the excess pressure to permit said valve to close, said last-named means being responsive to an abnormal condition in the generator tank.
24. In combination with a valve, a valve controlling mechanism therefor, comprising a movable member to which said valve is connected for movement therewith, means for providing different pneumatic pressures on opposite sides of said movable member to cause said member to move in a direction to open said valve, automatic means for reducing the said difference of pressure, and non-pneumatic means for closing said valve when the pneumatic pressures on opposite sides of said movable member are approximately equalized.
25. In combination with a valve for use in connection with a device having relatively adjustable parts, valve controlling mechanism for said valve comprising a mov-

able member to which said valve is connect-
ed for movement therewith, means for pro-
viding different pneumatic pressures on op-
posite sides of said movable member to cause
it to move in a direction to open said valve,
means operable by the adjustment of said
adjustable parts for equalizing the pressures
on opposite sides of said movable member,
and non-pneumatic means for closing said

valve when the pneumatic pressures on op- 10
posite sides of said member are approxi-
mately equalized.

Signed at New York city, New York, this
17th day of April, 1917.
